UNITED STATES PATENT OFFICE.

STEPHEN SHERMAN THOMAS, OF BLOOMFIELD, MISSOURI.

HUB-ATTACHING DEVICE.

SPECIFICATION forming part of Letters Patent No. 748,892, dated January 5, 1904.

Application filed September 10, 1903. Serial No. 172,664. (No model.)

To all whom it may concern:

Be it known that I, STEPHEN SHERMAN THOMAS, a citizen of the United States, residing in Bloomfield, in the county of Stoddard and State of Missouri, have invented certain new and useful Improvements in Hub-Attaching Devices, of which the following is a full, clear, and exact description, reference being had to the accompanying drawings, forming part of this specification.

My invention relates to an attaching device for vehicle-wheel hubs, the construction being such as to exclude the ingress of dust at the outer end of the hub and to provide for the removal and replacement of the hub on its axle-spindle without the requirement of a wrench or other implement, but merely by the rotation of the vehicle-wheel when the parts of the appliance are set in the proper positions to furnish engagement with the spindle axle-nut, as provided for.

The invention consists in features of novelty hereinafter fully described, and pointed out in the claims.

Figure I is a view, partly in elevation and partly in longitudinal section, of a vehicle-hub having my appliance therein. Fig. II is an end view of the hub with my appliance therein. Fig. III is a view of the outer end of the hub with the screw-disk and cam of my appliance omitted. Fig. IV is an inside view of the screw-disk and cam of the appliance. Fig. V is an edge view of the screw-disk and cam. Fig. VI is a similar view to Fig. III with the spindle axle-nut omitted. Fig. VII is a perspective view of one of the key-blocks. Fig. VIII is a view of the spring-washer used in connection with the turning stem of the cam of the appliance. Fig. IX is an enlarged section taken through the screw-disk and cam of the appliance.

1 designates the core of the outer half of a vehicle-wheel hub. This core is surrounded by a band 2, the forward end of which projects beyond the end of the core, as seen in Fig. I.

3 is an axle-spindle having the usual screw-threaded end 4, and 5 is a spindle axle-nut fitted to the threaded end of the spindle 3. The rim of the axle-nut is provided with a series of notches 6, the utility of which will be hereinafter explained.

7 designates a cup-shaped bushing seated within the hub-band 2 and having a flat inner end that fits against the forward end of the hub-core 1, to which it is secured by screws 8. (See Figs. III and VI.) The open outer end of the cup bushing 7 is provided interiorly with a screw-thread 9.

10 designates guide-ribs arranged in pairs on the interior of the cup bushing and extending longitudinally thereof to furnish dovetail guideways 11, (see Figs. I and VI,) which terminate at their inner ends in pockets 12, formed in the flat inner end of said bushing. 65

13 designates dovetail key-blocks which ride in the guideways 11. Each of these key-blocks bears a key-lug 14 and cam-fins 15. The key-lugs 14 are adapted to move inwardly to the notches 6 in the axle-nut 5 to place the key-blocks in engagement therewith for the service to be hereinafter fully explained, and the fins 15 receive the engagement of a cam, (to be described,) through the medium of which the key-blocks are reciprocated in their guideways.

16 designates a screw-disk that enters into the open outer end of the cup bushing 7 and is secured thereto by engagement with the screw-thread 9 interior of its bushing. The screw-disk is provided with a central aperture 19. (See Figs. I and IX.)

20 designates a circular cam having a flat head 21, provided with a pair of orifices 22. In the periphery of the cam 20 are a pair of inclined cam-grooves 23, which extend from the innermost points A of the cam to the outermost points B, as indicated in Fig. V. These cam-grooves receive the cam-fins 15 of the key-blocks 13, and when the cam 20 is rotated, as will be explained later, the fins by riding in the grooves cause reciprocation of the key-blocks to carry the key-lugs 14 inwardly to the notches in the axle-nut or re-cede them therefrom. The head 21 of the cam 20 bears a rotating stem 24, that passes through the aperture 19 in the screw-disk 16 and is provided with a slotted head 25. The head of this stem is designed to be engaged by a screw-driver or other suitable instrument to effect rotation of the cam 20, and thereby cause reciprocation of the key-blocks 13 in their guideways.

26 is a spring-washer interposed between

the head of the stem 24 and the screw-disk 16 and by which the stem-head is forced outwardly to hold the cam-head 21 in constant bearing with the inner face of the screw-disk 16.

17 designates recesses in the outer face of the screw-disk 16, which are designed to receive the prongs of a spanner or other suitable instrument, by which said screw-disk 10 may be rotated in inserting it or removing it from the bushing 7, in which it fits.

18 designates bosses on the inside face of the screw-disk 16, which are placed in alignment with the orifices 22 in the cam-head 21.

15 These bosses are designed to serve as catches for engagement in said orifices to yieldingly hold the cam 20 from rotation after the orifices have been turned thereto in the rotary movement of the cam to reciprocate the key-blocks 13.

20 By this arrangement the cam is held in a stationary position while the key-lugs 14 of the key-blocks are withdrawn from the notches 6 of the axle-nut. When the cam 20 is rotated to carry the key-blocks 13 into

25 the notches in the axle-nut, the bosses 18 are forced out of the orifices 22 in said cam and the spring-washer 26 tensely holds the cam 20 from movement, thus serving its purpose to prevent the blocks from being withdrawn

30 from the nut while oiling the axle-spindle.

I prefer to form the bosses 18 by upsetting the metal in the screw-disk 16 when the spanner-receiving recesses 17 therein are produced, inasmuch as such recesses may be

35 made by the use of a punch, and when so produced the metal at their locations is struck to the opposite side of the screw-disk, and the bosses are thereby produced in the proper positions and without extra expense in the

40 making of the disk.

In the practical use of my hub-attaching device the parts are operated as follows: The hub is placed upon the axle-spindle while the screw-disk 16, cam 20, and key-blocks 13 are absent therefrom. The axle-nut 5 is then screwed onto the thread of the axle-spindle and two of its notches 6 are brought into alignment with the guideways 11 in the cup bushing 7. The fins 15 of the key-blocks 13

45 are then seated in the inclined cam-grooves 23 of the cam 20, and the said key-blocks are entered into the guideways 11 in the cup bushing. The screw-disk 16 is then screwed into the bushing 7 by the use of a suitable

50 spanner, and at the same time the cam 20 is held from rotation through the medium of a screw-driver or other implement placed in engagement with the slotted head 25 of the cam-head stem 24. When the screw-disk has

55 been screwed home, it will be found that the hub will turn freely on the axle-spindle, and the key-blocks 13 will occupy the positions seen in Fig. I, where they are out of engagement with the axle-nut 5. All of the interior parts of the device back of the screw-disk 16 are thereby sufficiently inclosed by

said disk, and the ingress of dust or dirt there-to is excluded by said disk.

Whenever it may be desired to remove the vehicle-wheel from the axle-spindle, this may 70 be readily accomplished by the following procedure: By placing a screw-driver or other implement in engagement with the head of the rotating stem 24, and thereby rotating the cam 20, the key-blocks 13 are reciprocated inwardly, owing to their fin engagement with the cam, and as a consequence the key-blocks are moved inwardly until their key-lugs 14 75 enter the notches 6 in the axle-nut to lock said nut to the bushing 7, in which the key-blocks ride. Then upon backward rotation of the vehicle-wheel being imparted thereto the key-blocks 13 through their engagement with the axle-nut cause said nut to be unscrewed from the threaded end of the axle-spindle, and the wheel-hub may be slipped from the axle without disturbing the mechanism within it. When the wheel-hub is replaced, it is rotated in the opposite direction from that in which it was turned to remove it, and the axle-nut, being still held by the key-lugs, is again screwed onto the threaded end of the axle-spindle, thereby putting the parts in the same condition as they occupied just previous to the removal of the hub. The next step consists in placing the parts in proper position to permit free rotation of the wheel-hub on its spindle. This is done by rotating the cam 20 backwardly from its previous rotation to thereby withdraw the 100 key-blocks 13 from the inward positions they previously occupied and retract the key-lugs 14 from engagement with the notches of the axle-nut, so that the hub may rotate freely on its spindle.

I desire to call attention to the fact that the bushing 7 cannot become displaced in the hub-band in which it is seated and lost therefrom, owing to the fact that the axle-nut rim projects over the screws 8, which secure said bushing to the hub and therefore prevent the turning of said screws during the use of the hub.

I do not desire to be limited to the particular construction of the hub in respect to the hub-band and the bushing within it, including the manner of securing said bushing, as it is obvious that instead of slipping the bushing into the hub-band from the outer end of said band it may be introduced into the band from the rear before the band is put in place on the hub-core and in such instance be held from slipping out of the band, owing to the outer end band being smaller than the inner end. It is also evident that the hub-band 115 may be omitted and the bushing applied directly to the hub without departing from the spirit of the invention.

I claim as my invention—

1. In a device of the character described, 130 the combination with an axle-spindle, of a notched axle-nut fitted to said spindle, a hub

5 mounted on said spindle, reciprocating key-blocks in said hub for engagement in the notches in said axle-nut, a disk seated in said hub, a cam rotatably connected to said disk and having engagement with said key-blocks, and means for yieldingly holding said cam from rotation, substantially as set forth.

10 2. In a device of the class described, the combination with an axle-spindle, of a notched axle-nut fitted to said spindle, a hub mounted on said spindle, reciprocating key-blocks in said hub for engagement in the notches of said axle-nut, a disk seated in said hub, a cam rotatably connected to said disk and having engagement with said key-blocks, and a spring interposed between said disk and a part carried by said cam whereby said cam is yieldingly held to said disk, substantially as set forth.

15 3. In a device of the character described, the combination with an axle-spindle, of a notched axle-nut fitted to said spindle, a hub mounted on said spindle, reciprocating key-blocks in said hub for engagement in the notches in said axle-nut, a disk seated in said hub, an apertured cam rotatably connected to said disk, and having engagement with said key-blocks, a spring-washer for holding said cam to said disk, and bosses on the inner face of said disk to enter the apertures in said cam for the purpose of holding the cam from rotation, substantially as set forth.

20 4. In a device of the character described, the combination with an axle-spindle, of a notched axle-nut fitted to said spindle, a hub mounted on said spindle, reciprocating key-blocks in said hub for engagement in the notches of said axle-nut, each of said key-blocks having a fin, a disk screwed into said hub, a cam rotatably connected to said disk and having spiral grooves for engagement with said fins to impart reciprocation to the key-blocks, and means for yieldingly holding said cam from rotation, substantially as set forth.

25 5. In a device of the class described, the combination with an axle-spindle, of a notched

30 axle-nut fitted to said spindle, a hub mounted on said spindle, reciprocating key-blocks in said hub for engagement in the notches of said axle-nut, each of said key-blocks having a fin, a disk screwed into said hub, a cam rotatably connected to said disk and having spiral grooves for engagement with said fins to impart reciprocation to the key-blocks, and a spring interposed between said disk and a part carried by said cam whereby said cam is yieldingly held to said disk, substantially as set forth.

35 6. In a device of the character described, the combination with an axle-spindle, of a notched axle-nut fitted to said spindle, a hub mounted on said spindle, reciprocating key-blocks in said hub for engagement in the notches in said axle-nut, each of said key-blocks having a fin, a disk screwed into said hub, an apertured cam rotatably connected to said disk and having spiral grooves for engagement with said fins to impart reciprocation of the key-blocks, a spring-washer for holding said cam to said disk, and bosses on the inner face of said disk to enter the apertures in said cam for the purpose of holding the cam from rotation, substantially as set forth.

40 7. In a device of the character described, the combination with an axle-spindle of a notched axle-nut fitted to said spindle, a hub mounted on said spindle, a bushing in said hub provided with dovetailed guideways, dovetailed key-blocks reciprocatingly positioned in said guideways, each of said key-blocks having a fin, a disk screwed into said bushing and a cam rotatably connected to said disk and having spiral grooves for engagement with said fins for the purpose of reciprocating said key-blocks into and out of the notches in said axle-nut, substantially as set forth.

45 STEPHEN SHERMAN THOMAS.

In presence of—

T. BEN. TURNBAUGH,
BERT SMITH.
